Application December 21, 1933, Serial No. 703,475

4 Claims. (Cl. 164—60)

My invention relates to the art of rolling metal in strip form and, in particular, to a shear for trimming the edges of a strip at various stages in the rolling process.

5 Certain features of the present disclosure are also described and claimed in my U. S. Patent No. 1,985,856, granted December 25, 1934, for shears. According to the present practice of making thin material, hot rolled strip about .1" thick is cold rolled to the desired final gauge in long lengths. 10 One method of rolling involves the use of a single stand of rolls and the passage of the material back and forth through such stand the required number of times to produce the desired finished gauge. In the manufacture of strip according to this method, it is found that the hot rolled strip is characterized by edge defects of various kinds which it is desirable to remove before cold rolling. After the completion of the cold rolling, 15 furthermore, the product does not have perfectly straight edges and it is, therefore, desirable to perform a finishing edge-trimming operation.

My invention provides an apparatus for performing the necessary edge trimming operations in the cold rolling of strip metal with the utmost ease and accuracy. In accordance with my invention, I provide a pair of housings slidable along a suitable supporting base. Each housing is provided with spindles carrying cooperating disc shears for removing an edge of a long strip. The 20 housings are adjustable toward and from each other and a common drive for the spindles in both housings is provided.

The invention also includes means for diverting from the path of the strip being sheared, the edge portion which has been removed therefrom, and the chopping of such edge ribbon into a plurality of short pieces which can be readily handled. The shears for chopping the edge ribbons are mounted on the housings supporting the trimming shears and in alignment with the latter. A common drive is provided for the chopping shears. Entrance and exit pinch rolls aid in feeding the material to and through the shear. 25 The pinch rolls are driven from the same power source as the edge trimming shears and are geared to rotate at the same peripheral speed as the latter. The pinch roll and edge trimmer drive, however, includes a slip clutch so that the material is not subjected to excessive stress in case it is pulled through the shear at a speed greater than the peripheral speed of the pinch rolls and edge trimming discs.

For a complete understanding of the invention, 30 reference is made to the accompanying drawings

illustrating a present preferred embodiment. In the drawings:

Figure 1 is a plan view showing the shear associated with apparatus for feeding material to and pulling it through the shear;

Figure 2 is a sectional view substantially along the line II—II of Figure 1 showing in elevation parts illustrated diagrammatically therein;

Figure 3 is a side elevation with the pinch rolls removed;

Figure 4 is a side view of one of the shear housings from the inside, to enlarged scale;

Figure 5 is a partial plan view showing the shear cutters and guides;

Figure 6 is a partial sectional view along the line VI—VI of Figure 4, certain parts being rotated into the plane of section for the sake of clearness;

Figure 7 is a side elevation of a cutter holder; and

Figure 8 is a longitudinal section therethrough along the line VIII—VIII of Figure 7.

In the manufacture of thin, cold rolled strip, the hot rolled strip is usually wound in loose coils. The cold rolling of strip is usually effected while the material is subjected to considerable tension. For this reason, the coil of strip entering the cold mill must be wound tightly since otherwise it would be impossible to maintain a uniform tension thereon. It is customary, therefore, to wind the loosely coiled hot strip into a tightly wrapped coil on a mandrel adapted to be supported adjacent the mill for feeding the tightly wound strip thereto. I take advantage of the operation of winding the loosely coiled hot strip tightly on a mill mandrel to remove the defective edge portions of the strip. For this purpose, I employ a shear 10 located between the loosely wound coil 11 of hot strip and a mandrel 12 adapted to be driven by any convenient means for winding the hot strip thereon in a tight coil. The shear 10 comprises a base 13 having shear housings 14 and 15 slidable therealong, as well as entrance and exit pinch rolls 16 and 17 on opposite sides of the shear housings.

45 In each of the housings 14 and 15 is journaled a spindle 18 mounted therein in fixed bearings. The spindles 18 have cutting discs 19 attached thereto. Each of the housings is further provided with a shear spindle 20 having a disc cutter 21 thereon cooperating with the cutter 19. Adjusting wedges 22 and 23 are provided for properly positioning the spindle 20 relative to the spindle 18.

50 The spindles 18 and 20 are driven from a main power shaft 24 through back gears 25, the lower

one of which meshes with a pinion 26 on the shaft 24. The back gears mesh with gears 27 on the spindles. The shaft 24 is driven by a motor 28. The motor is connected to the shaft through a pinion stand 29 and a slip clutch 30 which permits the pinion stand to run ahead of the motor 28. The shaft 24 is journaled in bearings 31 on the base 13. The pinions 26 are elongated to permit lateral adjustment of the housings 14 and 15 without disturbing the drive for the cutters 19 and 21.

An adjusting screw shaft 32 is journaled in bearings on the base 10 and is adapted to be actuated by a hand wheel 33. The shaft has oppositely threaded portions traversing nuts fixed to the bottom of the housings 14 and 15. On rotation of the screw shaft 32, the housings move toward or away from each other on rails 34 and 34a carried by the base 13.

Cross rods 35 are slidably supported on opposite sides of the housings 14 and 15. Bars 36 extending between the rods 35 constitute a guide table for supporting the material indicated at M in its passage through the shear.

Each of the housings 14 and 15 also provides bearings for a pair of chopper spindles 37 and 38. Each spindle carries a cutter holder 39 having cutters 40 secured thereto. The cutters on one spindle cooperate with those on the other to effect a transverse shearing operation. The spindles 37 and 38 are geared together by the gears 41. The spindles 38 carry driving gears 42 which mesh with pinions 43 on a power shaft 44 journaled on the base 13 parallel to the shaft 24. The shaft 44 is driven by a motor 45 through a reduction gear 46.

Deflecting guides 47 are bolted to the inside of each of the housings 14 and 15. As shown in Figure 4, these guides extend beyond the point of tangency of the disc cutters 19 and 21 and engage the edges of the advancing material. After the material has passed the cutters 19 and 21, the sheared-off edge portion thereof follows the guides 47 downwardly and is fed between the spindles 37 and 38. The trimmed edge ribbon is thus cut into short lengths by the cooperation of the cutters 40 on the spindles, as shown in Figure 2.

The pinch rolls 16 and 17 may be of any suitable construction, such as that illustrated in Figures 1 and 2. The function of the pinch rolls, of course, is to grip the material M and feed it through the shear. The pinch rolls are driven through flexible joints 48 extending from the pinion stand 29.

The spindles 37 and 38 have their ends tapered as at 49. The bore of the holders 39 is similarly tapered, as shown in Figures 6 through 8. The holders are thus secured to the spindles by a friction fit. The holders 39 are designed as shown in Figure 7 so that the cutters 40 are not precisely radial but disposed at a slight angle to a radial plane. Because of the friction fit of the holders on the spindles, and the fact that the former are rotatable on the latter when the frictional fit is released, the holders may be adjusted angularly relative to the spindles so that the cutters on the two holders will properly cooperate after grinding the surfaces intersecting to form the cutting edge, without the necessity of shimming up the cutters. By tilting the cutters 40 slightly from a radial plane, the necessary clearance at the exposed edge of the cutter is obtained without grinding. At the same time, the symmetry of the section of the cutter is retained so that four cutting edges are provided instead of two.

This also avoids the expensive grinding of clearance back of the cutting edge, which has usually been necessary heretofore.

As previously indicated, the apparatus described so far is useful both for trimming the edges of hot rolled strip on its way to the cold mill and the trimming of the edges of the cold rolled strip before it is sent through the scrubber to the flying shear, which cuts the strip into lengths, and the piler. In the former case, the edge trimming of the hot strip is preferably effected as the material is being wound tightly on the mill mandrel preparatory to the first pass through the cold mill. In order to wind a tight coil, the mandrel, of course, must be driven. As the size of the coil on the mandrel 12 increases, the linear speed of the material increases if the angular speed of the mandrel is maintained. Regardless of the actual peripheral speed of the material, however, the pinch rolls 16 and 17 and the cutter discs 19 and 21 operate at the same peripheral speed, since they are all driven from a common source, namely, the pinion stand 29 and the motor 28. The slip clutch 30 between the motor and the pinion stand permit the pinch rolls and shear discs to run ahead of the motor 28 as the speed of the material increases without, however, affecting the relative peripheral speeds of the pinch rolls and shear discs, which are always maintained equal. If the thickness of the material is such that the torque applied to the mandrel 12 will not cause the pinch rolls to run ahead of the motor 28, the latter assumes its normal share of the effort required to feed the material through the shear.

As the shearing proceeds, of course, the edge ribbons are diverted from the path of the main body of the strip and are chopped into small pieces by the cutters 40. These pieces are in condition for convenient handling preparatory to returning to the open hearth furnace as scrap.

The operation for finishing edge trimming is about the same as that described above. Usually the load imposed by the material on the shears is small enough to permit acceleration of the strip, cutters, and pinch rolls as the coil on the winding-up mandrel increases in size, bringing the slip clutch 30 into operation. Under this condition, the pinch rolls and shear discs run ahead of their driving motor but maintain their equal peripheral speeds. Instead of coiling the sheared strip, it may be drawn through the shear by a roller leveler which feeds it to a cutting-up shear.

From the foregoing description, it will be apparent to those skilled in the art that my invention provides a strip shear having numerous important advantages. In the first place, the edge ribbons trimmed from the strip are diverted from the path of the body portion thereof, and chopped into short lengths for convenient collection and disposal. This is a marked advantage over the previous practice of permitting these ribbons to accumulate on the floor of the mill and obstruct the movements of workmen, as well as create a dangerous hazard by reason of the sharp edges of the strip. Since the chopping shears are in direct alignment with the edge trimming shears, there is no tendency for the former to pull the strip laterally of the disc cutters. The housings carrying the disc cutters, as well as the chopping shears, are easily adjustable, and relation of the two sets of shears is not altered by such adjustment. The adjustment, furthermore, does not require any disengagement of the drive for either of the two sets of cutters.

The pinch rolls and edge trimming shears being driven by a common source of power, always operate simultaneously and are designed to have the same peripheral speed to prevent buckling or looping of the material as it passes through the shears. It is obvious that the simple mechanical connection between the pinch rolls and the shears is more desirable than any complicated electrical control system for synchronizing the speeds of the various units could possibly be. The slip clutch between the motor and the pinion stand permits the pinch rolls and shears to overrun if the speed of the material exceeds the peripheral speed at which the pinch rolls are normally driven by the motor. At the same time, the pinch roll motor carries its proper load in shearing heavy material. The entire apparatus is useful, not only for trimming the rough edges from the hot rolled strip, but also for providing straight edges on the finished cold rolled strip.

While I have described only one modification of my invention, it will be apparent that numerous changes in the structure disclosed may be made without departing from the spirit of the invention or the scope of the appended claims.

I claim:

1. In an edge trimming shear for strip, a pair of housings, cooperating disc cutters rotatably mounted in each of said housings, pinch rolls for

advancing the strip through the shear, and a common drive for the cutters and pinch rolls, including a prime mover and a slip clutch.

2. A shear comprising a pair of housings, at least one of which is adjustable relative to the other, edge-trimming shears journaled in said housing, and chopping shears journaled in said housing adapted to sever the ribbon trimmed by the edge-trimming shears, a common drive shaft for the chopping shears in said housings, said shaft having an elongated pinion thereon meshing with gears driving the chopping shears in at least one of said housings.

3. A shear for cutting material in lengths comprising at least a pair of blades mounted for rotation about spaced axes whereby to cooperate in cutting material passing therebetween, at least one of said blades being mounted in a rotatable sleeve, said sleeve having an axial external slot parallel to the axis of the sleeve for receiving the 20 blade, a side wall of the slot being disposed at a slight angle to a radial plane through the sleeve, whereby to provide the blade in said slot with clearance to pass the cooperating blade.

4. The apparatus defined by claim 3 characterized by said one of said blades being a flat bar having a substantially rectangular section.

ARCHIBALD D. EVANS.
